SELF OPERATING FILLING STATION

Filed July 5, 1927

INVENTOR.

L. P. Starkey

BY J. D. Callanen

ATTORNEY.

UNITED STATES PATENT OFFICE.

LEWIS P. STARKEY, OF FORT COLLINS, COLORADO.

SELF-OPERATING FILLING STATION.

Application filed July 5, 1927. Serial No. 203,571.

This invention relates to vending machines and more particularly to machines for dispensing gasoline in measured quantities, as shown and described in my Letters Patent No. 5 1,650,882, issued Nov. 29, 1927, of which the present application is a continuation as to all matter common to both.

It is an object of the invention to provide in a machine of the above described character, a 10 simple, reliable and efficient mechanism to prevent the operation of the machine by an inserted coin, in case the merchandise (represented in the illustrated embodiment of the invention by gasoline) is exhausted or 15 diminished to such a degree that an amount equivalent in value to the inserted coin, cannot be obtained.

Other objects of the invention are to be 20 found in details of construction and novel arrangements and combinations of parts as will fully appear in the course of the following description.

In the accompanying drawings in the several views of which like parts are similarly 25 designated.

Figure 1 represents a partially sectional side elevation of a coin-controlled vending machine in which the improvements according to the present invention are embodied,

30 Figure 2, an enlarged fragmentary sectional view of the circuit breaking appliance associated with the supply tank of the machine as illustrated in Figure 1, together with a diagrammatic representation of the circuit,

35 Figure 3, a face view of a portion of the machine, showing the coin slot and the means for preventing the insertion of coins or checks in accordance with the present invention,

40 Figure 4, a section taken on the line 4-4, Figure 3, and

45 Figure 5, a section similar to Figure 4, showing the coin excluding means in its inoperative position when the coin slot is open to admit deposited coins to the operating mechanism of the machine.

The machine as shown in the drawings, 50 comprises a stand 5 of ornamental design in which the operating mechanism is enclosed, and a tank 6 preferably buried in the ground, which represents the reservoir or source of supply from which the gasoline or other liquid to be dispensed by the machine is drawn by the operation of a pump 7 installed in the base of the stand.

In the upper portion of the stand is a container 8 having an outlet in a sump 9 beneath its bottom, to which is connected a valve controlled discharge pipe 10 extending outside the stand. The discharge pipe may have a coupling for the attachment of a hose through 55 which the liquid is conducted to the gasoline tank of an adjacently parked automobile, which for obvious reasons has not been shown in the drawings.

Liquid drawn from the supply tank by the 60 pump 7 is conducted to the container through a pipe 12 having its outlet in the lower portion thereof, and liquid in excess of the predetermined quantity or quantities to be dispensed in the operation of the machine, is returned to the tank through overflow pipes 13 connected with a return pipe 14. The pump is connected with an electric motor 15 which is set in motion by a coin deposited in the 65 machine.

The mechanism provided for this purpose includes in the construction disclosed in the parent application herebefore referred to, a circuit-closing appliance actuated by the deposited coin, and a float in the container by 70 which the coin is released after the liquid in the container has risen to a predetermined level.

The mechanism has not been shown in detail in the drawings nor will it be further described inasmuch as it forms no part of the 75 present invention.

The coins are deposited in the machine through a slot 16 in the upper portion of the stand, which connects with a downwardly 80 ranging chute 17, it being understood that the coins passing through this chute actuate the before-mentioned circuit-controlling appliance.

For the purpose of rendering the machine 85 inoperative when the liquid in the supply tank 6 has been exhausted or diminished to a degree that the remaining quantity is insufficient to fill the container 8 to the required level, check or coin excluding means are provided in the form of a weighted door or gate 100 18 adapted to close the coin slot at the upper end of the chute.

The gate is normally suspended above the coin slot at an end of a lever 19 whose opposite arm constitutes the armature of an electro-magnet 20 which is supported on a bracket 21 at the outside of the coin chute. The elec-

tro-magnet is in a circuit controlled by a circuit breaker 22 which for convenience may be mounted in a box 23 upon the supply tank 6. The circuit breaker normally closes the circuit of the electro-magnet 20 and automatically breaks the same when the liquid in the tank falls below a predetermined low level.

The circuit breaker, to this end, comprises a cylindrical chamber 24 supported upon the screw-threaded upper end of a tube 25 which extends through an opening in the top of the tank, into the box 23. The tube provides a housing for the stem 26 of a float 27 disposed below the lower end thereof.

The upper end of the stem connects with a flexible diaphragm 28 supported in the chamber 24, in contact with the cylindrical wall thereof. The diaphragm carries a contact piece 29 adapted to be brought into engagement with the lower end of an adjustable screw-threaded contact rod 30 which is supported in a correspondingly screw-threaded plug 31 closing an opening at the top of the chamber.

The wall of the chamber 24, the contact piece 29, and the diaphragm 28 are all made of current conducting material so that a current conducted to the wall of the chamber will pass to the contact piece 29 and thence to the contact rod 30 when the contact piece is in engagement therewith. The wall of the chamber and the contact rod are provided with binding screws 32 and 33 for the connection of conductors of electricity 34 and 35 included in the circuit of the electro-magnet as shown in Figure 2.

When the supply tank contains liquid above its low level determined by the lower end of the guide tube, the float 27 held in engagement with the tube, causes the diaphragm to flex upwardly and thereby carry the contact into engagement with the end of the rod. The circuit thus being closed in the chamber, energizes the electro-magnet with the result that the armature lever is held in the position in which the weighted gate is elevated above the coin slot as shown in Figure 5.

If, however, the liquid in the tank falls to a level below the end of the guide tube, the float will follow the downward movement of the liquid by flexure of the distorted diaphragm, with the result that the circuit is opened, the electro-magnet is deenergized and the gate is permitted to drop to the position in which it closes the coin slot as illustrated in Figure 4.

It will thus be seen that as long as there is a quantity of liquid in the supply tank, sufficient to fill the container to the level determined by the overflow, the gate is held in the open position and coins may be freely inserted in the chute through the coin slot, to operate the mechanism of the machine as hereinbefore described.

As soon, however, as the liquid in the tank

is insufficient to fill the container, the gate drops, and coins are excluded from the mechanism until the supply tank has been refilled.

To prevent fraudulent operation of the machine through the depositing of spurious coins, washers or other articles, the chute has immediately below the coin slot 16, an opening 36 into which projects a prong 37, the upper end of which is beveled in a plane with the inclined wall 38 in which the opening is formed. Coins deposited through the slot 16, pass across the opening before dropping into the coin chute proper, but washers or other perforated slugs will be caught by the prong and held in suspension on the angularly bent lower portion 39 thereof.

Having thus described the novel improvements included in the vending machine, it is to be understood that variations in the construction and arrangement of the parts there- may be resorted to within the scope of the invention as defined in the hereunto appended claims.

Having thus described my invention, what I claim and desire to secure by Letters Pat- ent is:—

1. A vending machine comprising a reservoir, mechanism for dispensing liquid from the reservoir by the insertion of a coin in the machine, a device to obstruct the passage of coins to the mechanism, an electric appliance to actuate the device, a circuit for the appliance, and a circuit breaker in the circuit, including a diaphragm, contacts to be brought in engagement by movement of the dia- phragm, and a float controlling the movement of the diaphragm by movement of liquid in the reservoir.

2. A vending machine comprising a reservoir, mechanism for dispensing liquid from the reservoir by the insertion of a coin in the machine, a device to obstruct the passage of coins to the mechanism, an electric appliance to actuate the device, a circuit for the appliance, and a circuit breaker in the circuit, including a diaphragm, contacts to be brought in engagement by movement of the dia- phragm, and a float controlling the movement of the diaphragm by movement of liquid in the reservoir, and a stop restricting the movement of the float.

3. A vending machine comprising a reservoir, mechanism for dispensing liquid from the reservoir by the insertion of a coin in the machine, a device to obstruct the passage of coins to the mechanism, an electric appliance to actuate the device, a circuit for the appliance, and a circuit breaker in the circuit including a tube extending in the reservoir, a stem movable in the tube, a diaphragm controlling the movement of the stem, contacts disposed to be brought in engagement by movement of the diaphragm, and a float on the stem below the tube.

4. A vending machine comprising a reser-

voir, mechanism for dispensing liquid from the reservoir by the insertion of a coin in the machine, a device to obstruct the passage of coins to the mechanism, an electric appliance on liquid in the reservoir and in operative relation to the circuit breaker to break the circuit when the liquid falls to a predetermined level.

- 5 in insulated relation to liquid in the reservoir, a circuit breaker in the circuit, and a float outside the circuit adapted to be supported

In testimony whereof I have affixed my signature.

LEWIS P. STARKEY.
